CARBURETOR

Fremont Stokes, Clarksville, Ark.; W. E. Johnston administrator of said Fremont Stokes, deceased

Application November 27, 1931, Serial No. 577,607

13 Claims. (Cl. 261—78)

This invention relates to carburetors and it has particular relation to a novel and extremely simple apparatus for mixing fuel and air and feeding the mixture to an internal combustion engine.

Most carburetors used today in connection with automobile engines and the like are of complicated construction and are inoperative unless associated with a vacuum tank or a fuel feed pump.

The primary object of this invention is to provide a carburetor of unusually simple construction which obviates the necessity of using either a vacuum tank or a fuel pump.

15. A further object of my invention is to provide a simple and efficient carbureting device characterized by a novel fuel and air mixing nozzle and air controlling means which constitute its sole essential operative parts.

20. A still further object of this invention is to provide an extremely efficient carburetor which effects great economies in fuel consumption by thorough atomization or vaporization of the fuel and complete integration thereof with air to form a highly combustible fuel charge.

25. A further object of this invention is to provide a direct feed for fuel between a supply tank and an internal combustion engine, and in connection therewith to provide a novel charge forming device operative to take fuel directly from the tank, integrate the same with air to form a combustible charge and deliver the same to the engine as may be required under varying conditions of engine speed and load.

30. Another object of this invention is to provide a carburetor which, in its simplest form, involves a minimum of moving parts and therefore will not become out of order through use and require repair.

40. For a better understanding of the invention reference may be had to the accompanying drawings forming a part of the disclosure, wherein:

Fig. 1 is a side elevational view of a preferred embodiment of the invention, partly broken away 45 to disclose normally hidden parts,

Fig. 2 is a sectional view taken substantially on the line 2—2 of Fig. 1,

Fig. 3 is a central vertical sectional view of the structure taken on the line 3—3 of Fig. 2, illustrating the nozzle and by-pass constructions in greater detail,

Fig. 4 is a detail sectional view taken on the line 4—4 of Fig. 1, illustrating a form of fuel feed control valve which may be utilized, and

Fig. 5 is a detail sectional view taken substantially on the line 5—5 of Fig. 1.

Fig. 6 is a view more or less diagrammatic, showing a direct feed for fuel from a supply tank to an engine, and with the device of Fig. 1 interposed therein to perform the dual function of fuel supplying and fuel carbureting.

In order that the functioning of my invention may be clearly understood, brief consideration will first be given to the principles which control its operation. Substantially all carbureting devices for internal combustion engines are independent in their operation upon the vacuum, or evacuated condition, produced in the intake manifold of the engine as a means of carbureting the fuel and supplying the same to the engine cylinders. The ordinary carburetor is provided with a fuel reservoir to which fuel is supplied from the supply tank by means of a fuel pump or vacuum tank. By the use of suitable instrumentalities the fuel is vaporized in the carburetor, such as by passing the same through a small aperture under natural air pressure in accordance with the vacuum present in the engine manifold. Despite the changes and improvements in devices of such general character which have been made over a period of many years, it must be conceded that such devices are relatively inefficient in operation in that they fail to properly integrate the fuel and air with result that the fuel charge produced is not of as highly combustible character as it should be, in view of the potentialities of the fuel.

The present invention, like prior devices of the same general character, operates in accordance with the difference in pressure existing in the atmosphere and in the intake manifold of the engine, but such is to be differentiated from known devices in that such difference in pressure is utilized in a novel manner to produce the desired carburetion of the fuel. According to the proposed arrangement a portion of the air supply is admitted into a carburetor through suitable passages of small size under tremendous velocity to satisfy the evacuated condition produced by the engine. A small chamber connecting with a source of fuel is disposed in the carburetor adjacent to the air passages so that as the air passes into the carburetor the chamber will be evacuated, thus causing fuel from the source of supply to be forced into the same under natural air pressure existing at the source of fuel and thence pass outwardly to meet the high velocity air streams and thereby be thoroughly vaporized. To put the matter in other words, the

vacuum existing in the intake manifold of the engine causes an evacuated condition in the carburetor, which in turn causes air under a high velocity to rush therein. The incoming air causes an evacuated condition in the fuel chamber located in the carburetor, which in turn causes fuel under natural pressure from a source to be supplied thereto. The fuel is in turn brought into contact with the air, by which it is atomized. It will thus be understood that the principles of operation of the present device are materially different from those of carburetors of known type.

In view of what has just been stated, it will be appreciated that the present device operates to draw fuel from any source, and, therefore, does not require the use in connection therewith of a fuel pump or a vacuum tank. While such devices are not necessary to successful operation, they may be used if so desired. The same may be said with reference to the use of a float chamber, or reservoir, as a part of a carburetor.

By reason of its ability to obtain fuel from a source independent of any mechanical expedients or the force of gravity, my invention may be directly connected to a fuel tank, receive fuel therefrom under the differential pressure between the source and the intake manifold of an engine according to the principles of operation heretofore described, and thoroughly atomize the fuel so as to produce a highly explosive fuel charge for the engine.

Referring now to the drawings, I have in Figs. 1-5 illustrated one embodiment of my invention which broadly considered, comprises a housing, or main mixing chamber formed for attachment to the intake manifold of an internal combustion engine and provided with a main air intake. Extending into the housing is a small chamber, or dome, connecting with a source of fuel supply and located adjacent thereto is a series of air ports of small size through which air passes into the housing. The fuel chamber is closed with the exception of a series of small openings at the lower end thereof adjacent and extending preferably at right angles to the air ports, such arrangement being calculated to cause the air passing in through the ports to evacuate the chamber, thus causing the same to be filled with fuel from the supply. The fuel from said chamber thereupon passes outward from the openings where it meets the air rushing into the housing and is shattered thereby into small particles. A common type of butterfly valve is used to control the passage of the carbureted fuel mixture through the housing and a choke valve operating in unison therewith, controls the admission of air through the main air inlet. The two valves are manually controlled by the operator in the usual manner, and the main butterfly valve is capable of completely shutting off the passage through the housing. A by-pass is provided around the butterfly valve for permitting the flow of a small amount of fluid when the same is in closed position.

Preferably, and as shown, the housing 1 is cylindrical and is formed at one end with a flange 2 for attachment thereof to the intake manifold, not shown, of an internal combustion engine. The end 3 of the housing, remote from the flange 2, is closed except for a central opening 4 through which projects a fuel chamber, or nozzle, 5, formed intermediate its ends with a flange 6 for attachment with the end 3 by means of screws 7. It will be noted that the chamber 5 is closed at its upper end and is in communication with the

housing only through small apertures, hereafter to be described.

The chamber, or nozzle, 5, is provided with a central portion 8 adapted to act as a fuel inlet chamber and connecting with a source of supply through a pipe 9. At the lower end of the nozzle, and projecting through the inlet chamber 8, is mounted a regulating screw 10 having at its upper end a tapered portion adapted to seat in an opening 12 in the top portion, or nozzle portion, 13. Preferably, this top portion 13 is dome-shaped.

Disposed in the flange 6 are a series of apertures 14 of relatively small size and adapted to allow the admission under high velocity of air into the housing 1 under the vacuum caused by the engine. Disposed at the lower end of the top portion 13 of the fuel nozzle are a series of apertures 15 corresponding in number and position to the air apertures 14, and being located in close proximity and at right angles thereto. By such arrangement air passing in through the apertures 14 will create an evacuated condition in the chamber 13, which will thereupon receive fuel from the central portion 8 through the opening 12 from the source of fuel supply. Fuel from the chamber 13 will pass out through the apertures 15 to meet the air rushing in through the apertures 14 at right angles, and will be, thereby, broken up and thoroughly atomized.

The size of fuel and air apertures will be determined to some extent by the displacement of the engine by which my device is used, it being intended that the atomizing mechanism described serves without adjustment to supply an efficient fuel charge to an engine under all conditions of speed and load. As the engine speed varies the vacuum which renders my device operative will change and cause larger or smaller quantities of fuel and air to be supplied to the housing, or main chamber, 1, of the carburetor.

It will be appreciated that the quantity of air supplied through the apertures 14 is not enough to form a combustible fuel charge with the fuel supplied through the apertures 15, and that it is contemplated that the sole purpose in admitting air at such points is to provide means which will draw fuel to the carburetor from a suitable source and shatter such fuel into small particles in preparation for admixture thereof with sufficient air to constitute a highly combustible fuel charge. The housing, or main mixing chamber, 1, is provided at one side with an air intake 16 adjacent the end 3 through which air is admitted in quantity sufficient to form a combustible charge with the fuel. As heretofore pointed out, the butterfly valve 17 controls passage of fluid from the housing 1 to an engine with which it is connected. Said valve is centrally located, journaled on a shaft 18 and controlled by lever 19. The air inlet 16 is controlled by a similar butterfly valve 20, journaled therein on a shaft 21 and movable simultaneously with the valve 17 by means of connecting arms 22 and 23, actuatable by means of lever 18. Since the butterfly valve 17 will determine the quantity of fluid passing to an engine, and hence determine the quantity of air which, under the evacuated condition produced by the engine, can be drawn in through the air intake 16, the valve 17 controlling the air intake 16 is preferably adjusted so as to open and close simultaneously with the valve 17. It may be, however, that to insure the proper proportion of air necessary

to form a highly combustible fuel charge with the fuel supplied from the fuel chamber 13 through openings 15, that the valve 19 be at all times slightly less open than the valve 11. In 5 this connection it will be recalled that a certain amount of air passes into the mixing chamber 1 through the fixed air openings 14, which would decrease the quantity required to be supplied through the main air inlet 16. Any desired relation 10 in position between the valves 11 and 19 may be attained by adjusting either the connecting arms, 21 and 22, or by adjusting the valves with respect thereto.

With the arrangement of parts just described, 15 it is contemplated that when the engine to which the device is attached is running at idling speed, the butterfly valves 11 and 19 will be in substantially closed positions. To supply a proper fuel mixture under such conditions, a by-pass 23 is 20 located at one side of the housing, or main mixing chamber, 1, having a passage-way located therein communicating at 24 with the housing above, and at 25 with the housing below the valve 11 when the same is in closed position. Since 25 under such conditions the valve 19, controlling the main air supply, will also be closed, and since the air passing in through the fixed openings 14 is insufficient to form a combustible mixture with the fuel, an auxiliary air inlet 26 is provided in 30 the by-pass. A longitudinally extending partition 27 is provided in the by-pass between the fuel and air passages, and two adjustable screws, 28 and 29, are provided to insure the proper mixture of air and fuel suitable for the engine 35 when operating at idling speed.

The arrangement just described is of considerable value in insuring proper operation of the engine, since it has been found that the proportions of air and fuel best for the engine at 40 running speeds are not entirely satisfactory for the engine when the same is idling.

As heretofore pointed out, the fuel chamber, or nozzle, 8, is connected with a suitable source of supply through a pipe 9, and by reason of the 45 particular arrangement of parts heretofore described, fuel will be constantly supplied to the engine as long as the same is in operation. In so far as successful operation of the present carburetor is concerned, it is immaterial where the 50 same be positioned relative to the engine. It may be equally well employed for down-draft or up-draft carburetion. To prevent gravitational flow of fuel from the source of supply when on a steep down grade, and to prevent fuel from 55 being supplied to the engine when an automobile is coasting against the engine, which ordinarily would cause fuel to be supplied to the carburetor, it is proposed to employ an automatic valve which 60 will cut off the fuel supply to the carburetor under such conditions. To this end an auxiliary fuel saving device is provided in the fuel line 9, or at the junction between the fuel line and the fuel nozzle 8. As best shown in Fig. 4, such device comprises a casing 30, closed at one end by 65 means of a cap 31, and provided with a passage 32 intersecting the fuel line 9. A ball 33 rides in the passage 32. The device is so positioned with respect to an automobile that as the same tilts forward on a hill, the ball under the action of 70 gravity moves to restrict the flow of fuel through the pipe 9, the recessed seat 34 being provided at the end of the casing 30, associated with the pipe. As the automobile assumes its normal horizontal position, the ball will roll back toward the cap end of the casing to open the pipe. 75

To render this automatic fuel cut-off inoperative, or to restrict its operation in case it is desired to maintain the engine running on downgrades, a plunger, 35 extending into the passage 32 through the ball seat 34, is provided, the 5 same constituting a stop for the ball as the same moves to close the pipe 9. The plunger 35 may be conveniently controlled through a lever 36, extension member 37 and rod 38 from the dash of the automobile by means of a nob 39, as best 10 shown in Figure 6.

As heretofore generally stated, the carbureting device shown in Figures 1 through 5 is of such character as will enable the same to supply itself with fuel from any suitable source without 15 the necessity of using a fuel pump or vacuum tank. Such is the case by reason of the fact that fuel from a source is constantly supplied to the nozzle 8 by reason of the fact that air passing into the mixing chamber, 1, through openings 14 20 produces a partially evacuated condition in the top fuel chamber 13 of the nozzle from which the same passes outwardly through openings 15 to be vaporized and admixed with the incoming air from the openings 14, and thereafter to be 25 further mixed with the air passing in through the main air inlet 16. The ordinary float chamber, or reservoir, usually present in carburetors is thus eliminated, and my device may be directly connected with a fuel supply tank, and as 30 long as the engine is operating will take fuel therefrom adequate for the needs of the engine under varying conditions of speed and load. Successful operation is not dependent upon the action of gravity, but on the other hand, utilizes 35 the pressure of air operating at the fuel source to force fuel into the fuel chamber of the carburetor, and thence into the mixing chamber by reason of the evacuated condition produced by the engine therein. For this reason it is by no 40 means necessary that the carburetor be located at, or below, the level of the source of fuel.

In Fig. 6 I have illustrated a practical embodiment of my invention wherein the carburetor, 1, is shown applied to the intake manifold 45 40 of the engine in an automobile, the same being directly connected to receive fuel from the fuel tank 41, located at the rear of the car, through pipe 9. The various operative parts of my carburetor having heretofore been described 50 and being illustrated in Figs. 1 through 5, are shown more or less diagrammatical in Fig. 6. With the explanation above given it will be understood that the carburetor takes fuel through the line 9 from the fuel tank 41, atomizes and 55 admixes the same with air to form a highly combustible fuel charge, which is supplied to the engine through the intake manifold 40 as required. No special provision is made in the fuel tank in order to assure the proper feed to the carburetor, it being contemplated that such tank be of the type ordinarily used wherein a small hole is provided in the cap, or at some other convenient point in the tank, so that the fuel therein will be subject to atmospheric pressure. 60

From the foregoing description it is apparent that I have provided a novel and efficient device for the atomization of fuel and automatic means for securing economy in the use thereof.

It is to be particularly emphasized that whereas the modern trend in carburetors is towards highly complicated structures having numerous working parts, the carburetor of the present invention is simple to the extreme, cheap to manufacture, and having relatively few parts. Essen- 75

5 tially it comprises only a small chamber at-
tachable to the intake manifold of an internal
combustion engine, a fixed fuel nozzle connect-
ing with a source of supply, and a fixed air in-
5 take adjacent the fuel nozzle and formed rela-
tive thereto so as to insure thorough vaporiza-
tion of the fuel and admixture thereof with the
air. The efficiency of my device over other car-
buretors in effecting fuel economies and prevent-
10 ing carbonization of the engine cylinders by rea-
son of its superior fuel vaporizing and charge
forming ability has been demonstrated by actual
tests.

15 Although I have illustrated only one form
which may be employed in the practice of my
invention, it will be apparent to those skilled
in the art that the invention is not so limited, but
that the embodiment shown is capable of various
20 minor modifications, and that other embodi-
ments may be employed without departing from
the spirit of the invention or from the scope of
the appended claims.

I claim:

1. In a fuel supply system for an internal com-
25 bustion engine, a carburetor including a mixing
chamber, a fuel dome projecting into the mixing
chamber, a source of fuel connecting directly with
said fuel dome, the dome having apertures in its
30 side wall leading from the interior thereof into
the mixing chamber, and a high velocity air inlet
communicating directly with the atmosphere in
the wall of the mixing chamber surrounding the
dome and opposite the fuel apertures adapted to
35 cause the fuel to be supplied to the mixing cham-
ber in highly atomized condition.

2. In a fuel supply system for an internal com-
bustion engine a main fuel supply tank, a car-
buretor including a mixing chamber, a fuel dome
projecting into the mixing chamber through the
40 chamber wall and connecting directly to said fuel
supply tank, said dome having apertures in its
side wall connecting the interior thereof with the
mixing chamber, and minute apertures in said
45 mixing chamber wall positioned externally of and
about said dome and communicating freely with
the atmosphere to create a high velocity flow of
air to atomize and facilitate the supply of fuel to
the mixing chamber, and an additional main air
50 inlet to mix air with the atomized fuel and carry
it to the point of consumption.

3. A carburetor including a main chamber hav-
ing an opening in the wall thereof, a fuel atom-
izing element projecting into said main chamber
through said opening, the same being connected
55 to a source of fuel and comprising a cone-shaped
hollow dome member having apertures about its
base, a restricted inlet in said main chamber in
free communication with the atmosphere and
said fuel atomizing element and disposed in op-
60 posing relation to the fuel apertures through
which restricted inlet air enters at a high velocity
and maintains the interior of the atomizing ele-
ment in a partially evacuated condition and feeds
said fuel to the chamber.

65 4. A carburetor including a main chamber hav-
ing an opening in a wall thereof, a fuel atomizing
element projecting into said main chamber
through said opening, the same being connected
70 to a source of fuel and comprising a dome mem-
ber having apertures about its base, a plate ad-
jacent the base of said dome and forming part
of the wall of said main chamber, said plate hav-
ing apertures adjacent and at right angles to the
75 apertures of said dome member, through which
air enters at a high velocity and maintains the

interior of the atomizing element in a partially
evacuated condition and feeds said fuel to the
chamber.

5. In a carburetor for an internal combustion
engine, a mixing chamber having a port for the
admission of air and connecting to the intake side
of the internal combustion engine at one end,
spaced control valves operating in unison position-
10 ed in the chamber between the air port and
said end, a hollow fuel dome projecting into the
mixing chamber intermediate said valves through
the chamber wall, a source of fuel supply con-
necting with said fuel dome, the dome having
15 apertures in its side wall leading from the in-
terior thereof into the mixing chamber, and an
auxiliary high velocity air inlet in said wall of the
mixing chamber surrounding the dome adapted to
cause the fuel to be supplied to the mixing cham-
20 ber in highly atomized condition there to be
admixed with air entering through the main air
port.

6. In a carburetor comprising a mixing cham-
ber having a main air port and formed for at-
tachment to the intake manifold of an internal
combustion engine at one end, control valves oper-
25 ated in unison spaced within said chamber be-
tween the air port and said end, and an opening
in the chamber intermediate said valves, a fuel
atomizing element extending into said mixing
30 chamber through said opening, the same com-
prising an apertured fuel head and an apertured
flange adjacent the base of said head and pro-
viding an auxiliary air intake, the fuel and air
apertures being disposed in proximity and ex-
35 tends cross-wise of each other so that air en-
tering the mixing chamber through the apertures
will cause fuel to be drawn from the head into
the mixing chamber.

7. In a carburetor, a mixing chamber having a
main air port and formed for attachment at its
40 discharge end to the intake manifold of an in-
ternal combustion engine, spaced control valves
operating in unison positioned in the chamber
between the air port and the discharge end, a
fuel nozzle projecting through the chamber wall
45 and into the mixing chamber intermediate said
valves and connecting with a source of supply,
an auxiliary air inlet to the mixing chamber in
the chamber wall and communicating directly
50 with the atmosphere surrounding the fuel nozzle
for drawing fuel into the chamber, and a by-pass
in the wall of the mixing chamber around the
valve controlling the discharge therefrom opera-
tive when said valve is closed to conduct the fuel-
55 air mixture supplied by the fuel nozzle and auxil-
iary air inlet from the chamber to the discharge.

8. In a carburetor for an internal combustion
engine connected to a fuel supply tank, a chamber
having a port for the admission of air and con-
necting to the intake side of the internal com-
bustion engine at one end, spaced control valves
60 operated in unison positioned in the chamber,
the wall of the chamber at a point intermediate
said valves being provided with an opening, a fuel
atomizing device extending through said wall
opening and into the chamber, the same carrying
65 a fuel dome which extends into said chamber,
said dome having a plurality of fuel apertures at
its base opening into the chamber, the wall of
the chamber being provided with air apertures
extending adjacent and at right angles to the
70 fuel apertures for the purpose of creating a par-
tially evacuated condition in said dome, and for
drawing fuel from the supply tank, a manually
controlled needle valve controlling the admission
75

of fuel to the fuel dome, and a gravity actuated valve associated with said atomizer to control the flow of fuel under certain other conditions.

9. In a carburetor for an internal combustion engine connected to a fuel supply tank, a chamber having a port for the admission of air and connecting to the intake side of the internal combustion engine at one end, spaced control valves operated in unison positioned in the chamber,

10 the wall of the chamber at a point intermediate said valves being provided with an opening, a fuel atomizing device extending through said wall opening and into the chamber, the same carrying a fuel dome which extends into said

15 chamber, said chamber having a plurality of fuel apertures at its base opening into the chamber, the wall of the chamber being provided with an air aperture extending adjacent and at right angles to the fuel apertures for the purpose of

20 creating a partially evacuated condition in said dome, and for drawing fuel from the supply tank, a manually controlled needle valve controlling the admission of fuel to the fuel dome, a gravity actuated valve associated with said

25 atomizer to control the flow of fuel under certain other conditions, and a by-pass conduit adjacent the inner control valve to be utilized when said valve is closed.

10. A carburetor including a casing providing a mixing chamber, fuel supply means projecting into the chamber through the casing wall and having a fuel outlet comprising a series of side apertures which discharge directly into the chamber in the immediate vicinity of the chamber wall, high velocity air inlet means in said chamber wall in free communication with the atmosphere and opening directly into the chamber, said air inlet means surrounding the fuel supply means and being located below the level of, but in proximity to, the fuel apertures so that fuel will be drawn into the chamber in the path of the inrushing air.

11. A carburetor including a casing providing a mixing chamber, fuel supply means projecting into the chamber through the casing wall, a fuel outlet comprising a series of side apertures in said supply means located in close proximity to the chamber wall and discharging directly into the chamber, and restricted air apertures in said chamber wall opening directly into the chamber and at their outer ends being in free communica-

tion with the atmosphere, said air apertures being arranged in alignment with and in proximity to the fuel apertures so that the streams of air discharged will as they enter the chamber cause fuel from the supply means to be drawn into the chamber in the path of said air streams.

12. In a carburetor, a mixing chamber having a main air port and formed for attachment at its discharge end to the intake manifold of an internal combustion engine, spaced control valves operating in unison positioned in the chamber between the air port and the discharge end, a fuel nozzle projecting into the mixing chamber intermediate said valves and connecting with a source of supply, an auxiliary air inlet to the mixing chamber in free communication with the atmosphere the same comprising apertures in the side walls of said chamber and surrounding the fuel nozzle for drawing fuel into the chamber, said auxiliary air inlet communicating directly with the atmosphere and being operable to supply air when the control valves are closed, a by-pass in the wall of the mixing chamber around the valve controlling the discharge therefrom operative when said valve is closed to conduct the fuel-air mixture from the fuel nozzle and auxiliary air inlet from the chamber to the discharge, and a small adjustable supplemental air intake communicating directly with the by-pass.

13. In a carburetor for an internal combustion engine connected to a fuel supply tank, a chamber having a port for the admission of air and connecting to the intake side of the internal combustion engine at one end, spaced control valves operated in unison positioned in the chamber, an opening in the chamber wall intermediate said valves, a fuel atomizing device extending through said opening and into the chamber, the same carrying a fuel dome which extends into said chamber, said member having a plurality of fuel apertures opening into the chamber at its base in close proximity to the opening in the chamber wall, air apertures in the wall of the chamber communicating freely with the atmosphere and at right angles to the fuel apertures for the purpose of creating a partially evacuated condition in said dome, and for drawing fuel from the supply tank, and a manually controlled needle valve controlling the admission of fuel to the fuel dome.

FREMONT STOKES.
